UNITED STATES PATENT OFFICE.

GEORGE W. POWELL, JOSEPH L. SMITH, AND HOWARD E. DIXON, OF LA GRANDE, OREGON.

GLARESHIELD.

Application filed December 8, 1923. Serial No. 679,484.

To all whom it may concern:

Be it known that we, GEORGE W. POWELL, JOSEPH L. SMITH, and HOWARD E. DIXON, citizens of the United States, residing at La Grande, in the county of Union and State of Oregon, have invented certain new and useful Improvements in Glareshields, of which the following is a specification, reference being had to the accompanying drawings.

This invention relates to improvements in glare shields for automobile headlights and more particularly to a device of this character adapted to be arranged interiorly of the headlight.

An important object of the invention is to provide a device of this character which, while eliminating all direct rays from the lamp which pass upwardly or horizontally through the lens of the headlight, permits refracted rays of the parabolic reflector usually employed to pass from the lamp to illuminate the road.

A further object of the invention is to provide a glare shield of this character of such construction that the shield does not form a dead spot at the upper surface of the lens, where such shields are usually provided, but is so constructed that it actually permits filtration of rays therethrough for illumination of the road.

A further object of the invention is to provide a device of this character which may be very readily applied to standard constructions of headlights without in any manner interfering with the normal operation of the headlight.

These and other objects we attain by the construction shown in the accompanying drawings, wherein for the purpose of illustration is shown a preferred embodiment of our invention and wherein:—

Figure 1 is a vertical sectional view through a headlight embodying a glare shield constructed in accordance with our invention;

Figure 2 is a perspective of the glare shield removed;

Figure 3 is a section on the line 3—3 of Figure 5, illustrating the fact that the shield permits the passage of refracted light;

Figure 4 is a view of the shield looking upwardly and forwardly from the point of location of the headlight filament, this view illustrating the fact that the plates com-

pletely cut off all direct rays of the filament from the lens; and

Figure 5 is a rear elevation of the headlight rim and lens removed, showing the shield applied thereto.

Referring now more particularly to the drawings, the numeral 10 indicates the casting of a headlight, 11 the usual parabolic reflector disposed therein, 12 the illuminating element bulb, 13 the lens attaching rim, and 14 the lens shown in the present instance as consisting of a sheet of clear glass although it will be readily understood that the device may be applied to those headlights which depend upon their construction for the refraction of rays in such manner as to not provide a glaring light. In the usual construction of the headlight rim and lens, the internal diameter of the rim is slightly less than the external diameter of the headlight lens, so that the edges of the lens project beyond the inner edges of the rim and is held in position by means of clips 15 or the like carried by the rim engaging the inner faces of the lens. As will hereinafter appear, we employ these clips as a means for holding in position the glare shield constructed in accordance with our invention.

The glare shield proper consists of two plates 16 and 17, hereinafter referred to as the upper and lower plates, these plates combining when viewed from the point of location of the filament of the lamp to provide a triangle effectually cutting off all view of the edges of the lens as defined by the inner edge of the lens rim 13. The upper and lower plates 16 and 17 are inclined inwardly from the face of the lens, the inclination being upwardly and outwardly from this lens, the plates being in substantially parallel planes. The upper plate 16 is provided with a terminal portion 18 which is arcuately curved and overhangs the lower plate 17. This upper plate is substantially triangular in form. The lower plate is in the form of a triangle having an arcuate segment removed from the upper angle thereof, this arcuate segment aligning with the curved extension of the upper plate 16 and provided in the upper edge of the lower plate with a notch 19. The lower edge of the lower plate is provided with an angular extension 20 paralleling and in substantial

contact with the adjacent face of the lens, 110

which extension lies at the approximate center of the lens when the device is in applied position and effectually prevents direct rays from the illuminating element 12 from passing from the casing. These plates are each provided at their ends with extensions 21 by means of which they are attached to an annulus 22 having an internal diameter substantially equal to the internal diameter 10 of the lens, as defined by the lens rim, and an external diameter substantially equaling the true diameter of the lens. This annulus is placed against the inner face of the lens and is included in the clips 15 when the 15 same are employed to fasten the lens in position in the rim.

By comparative inspection of Figures 5 and 4, which latter figure is a rear elevation of the lens taken from a point approximating the filament of the illuminating element, it will be seen that it is impossible for direct rays from the lamp to pass through the lens if such rays are at an angle which permit these rays to blind the operators of oncoming vehicles, it being understood that the lower edge of the lower plate 17 is arranged at a point upon the lens to intersect such blinding rays. This comparison will further show that the combination of the 20 plates 16 and 17 will permit refracted rays from the filament to pass from the headlight, this detail being more clearly shown in Figure 3. It will, however, be obvious that since in order to pass these plates 25 the rays must come into contact with the parabolic reflector, these rays will be corrected and will issue from the headlight in approximately straight line so that they will not cause discomfort to the operators of 30 other vehicles.

Attention is now directed particularly to Figure 1. In this figure we have illustrated a vertical sectional view through the headlight taken through the plates 16 and 17 approximately centrally thereof. From this 45 figure it will be obvious that while direct rays are effectually cut off by the plates 16 and 17, at the same time in the space between the point of attachment of the plate 16 and the point of attachment of the plate 17 a space is left through which rays may 50 be deflected. Rays are deflected through this opening by reason of the fact that the notching of the upper end of the plate 17 exposes a considerable portion of the plate 16 to view and by reason of the fact that the inner face of the plate 16 and outer face of the plate 17 are highly polished as 55 is likewise the inner face of the plate 17. 60 It will be seen that forwardly directed rays reflected by the reflector 11 of the headlight striking against the plate 16 will be deflected downwardly against the outer face of the plate 17 and that from this plate they 65 will be again thrown forwardly through

the headlight lens. The curved terminal portion 18 of the plate 16 serves to deflect a portion of the direct rays from the bulb or illuminating element 12 against the outer face of the plate 17 so that they likewise pass through the opening. It will be noted that these rays in their deflection from the plate 17 are inclined downwardly toward the ground and accordingly will not be dazzling. 70

From the foregoing it is believed to be obvious that when provided with a glare shield constructed in accordance with our invention a headlight will be free from glaring direct rays which tend to confuse the drivers of oncoming vehicles. It will furthermore be obvious that the construction of the device is capable of a considerable range of change and modification without materially departing from the spirit of our invention and we accordingly do not limit ourselves to such specific structure as hereinbefore set forth except as herein-after claimed. 75

We claim:

1. The combination with a headlight embodying the usual illuminating element, parabolic reflector and lens, of a glare preventer arranged within the headlight at the upper portion of the lens thereof intercepting upwardly inclining direct rays from the illuminating element to prevent their passage through the lens but permitting the passage of refracted rays about the edges thereof, said glare preventer comprising spaced upper and lower plates arranged above the horizontal plane of the headlight illuminating element, the portions of the plates adjacent the lens being spaced, one of said plates being positioned to reflect light from the headlight illuminating element upon the other of the plates for refraction thereby through such space. 80

2. The combination with a headlight embodying the usual illuminating element, parabolic reflector and lens, of a glare preventer arranged within the headlight at the upper portion of the lens thereof intercepting upwardly inclining direct rays from the illuminating element to prevent their passage through the lens but permitting the passage of refracted rays about the edges thereof, said glare preventer comprising spaced upper and lower plates arranged above the horizontal plane of the headlight illuminating element having their adjacent faces highly polished to form reflectors, one of said plates being positioned to reflect light from the headlight illuminating element upon the other of the plates for refraction thereby through such space. 85

3. The combination with a headlight embodying the usual illuminating element, parabolic reflector and lens, of a glare preventer arranged within the headlight at the 90

- upper portion of the lens thereof intercepting upwardly inclining direct rays from the illuminating element to prevent their passage through the lens but permitting the passage of refracted rays about the edges thereof, said glare preventer comprising spaced upper and lower plates arranged above the horizontal plane of the headlight illuminating element affording a space therebetween 45
- 5 10 at the lens for the passage of light through the lens, one of said plates being positioned to reflect direct light from the headlight illuminating element and light from the illuminating element refracted by the reflector upon the other of the plates for refraction thereby through such space.
- 15 4. The combination with a headlight embodying the usual illuminating element parabolic reflector and lens, of a glare preventer arranged within the headlight at the upper portion of the lens thereof intercepting upwardly inclining direct rays from the illuminating element to prevent their passage through the lens but permitting the 50
- 20 25 passage of refracted rays about the edges thereof, said glare preventer comprising spaced upper and lower plates affording therebetween a space permitting passage of rays through the headlight, said plates inclining upwardly and rearwardly and having adjacent faces thereof highly polished, one of said plates having a portion reflecting light from the headlight illuminating element upon the other of the plates for refraction through such space. 55
- 30 35 5. The combination with a headlight embodying the usual illuminating element, parabolic reflector and lens, of a glare preventer arranged within the headlight at the upper portion of the lens thereof intercepting upwardly inclining direct rays from the illuminating element to prevent their passage through the lens but permitting the passage of refracted rays about the edges thereof, 60
- 40 45 for refraction thereby through such space.
- 50 55 6. The combination with a headlight embodying the usual illuminating element, parabolic reflector and lens, of a glare preventer arranged within the headlight at the upper portion of the lens thereof intercepting upwardly inclining direct rays from the illuminating element to prevent their passage through the lens but permitting the 65
- 60 65 passage of refracted rays about the edges thereof, said glare preventer comprising spaced upper and lower plates affording therebetween a space permitting passage of rays through the headlight, said plates inclining upwardly and rearwardly and having adjacent faces thereof highly polished, one of said plates having a portion reflecting light from the headlight illuminating element upon the other of the plates for refraction through such space, 70
- 70 75 75 for refraction thereby through such space, and other portions reflecting refracted light from the headlight reflector upon such other plate for refraction through such space, said other plate being notched to thereby increase the effective area of the first named plate which is exposed to the refracted rays of the reflector. 80
- In testimony whereof we hereunto affix our signatures.
